UNITED STATES PATENT OFFICE

WILBUR L. HOUSEMAN, OF SOMERTON, PENNSYLVANIA, ASSIGNOR TO STANDARD-TRUMP BROS. MACHINE COMPANY, OF WILMINGTON, DELAWARE, A CORPORATION OF DELAWARE

KNITTED FABRIC AND PROCESS OF MAKING THE SAME

Application filed October 30, 1929. Serial No. 403,392.

This invention relates to a plated knitted fabric and process of making the same, and relates specifically to a fabric of this type exhibiting multicolored effects of a peculiar 5 type.

Patterns of different colors have been produced in knitted fabrics by simultaneously feeding two, three or more threads to knitting needles and so manipulating the threads 10 or needles so as to cause either reverse plating or floating. The manipulation of two threads in various manners is well known in the art. Satisfactory methods of manipulating two or more threads are disclosed, for 15 example, in an application of William J. Schubert, filed June 6, 1929, Serial No. 368,-828 and in my prior applications, filed February 12, 1929 and February 20, 1929, Serial Nos. 339,335 and 341,374, respectively. The 20 type of mechanism used in my said applications is utilized in a preferred form of mechanism below described for carrying out the new process.

The broad object of the present invention 25 may be said to be the production of a knitted fabric of the plated type exhibiting peculiar multicolored effects. More specifically the invention has reference to fabrics of this character in which a great multiplicity of 30 pattern and color effects may be obtained without the necessity of frequent yarn changes or the production of an objectionably heavy fabric.

The objects and advantages of the invention 35 will be made clearer in the following description read in conjunction with the accompanying drawings, in which:

Fig. 1 is a diagrammatic developed view of 40 one form of mechanism adapted to produce the improved fabric;

Fig. 2 is a fragmentary plan view of the mechanism of Fig. 1;

Fig. 3 is a diagrammatic elevation of one 45 type of the new fabric producible by the mechanism;

Figs. 4 and 5 are sectional detail views showing portions of the mechanism;

Figs. 6 and 7 are views illustrating the 50 general appearance of two fabrics falling within the scope of the invention;

Fig. 8 is a diagram showing how other fabrics may be produced in accordance with the invention;

Fig. 9 is a view similar to Fig. 2 showing a mechanism for producing the elaborate 55 forms of fabrics of Fig. 8; and

Fig. 10 is an enlarged diagrammatic elevation of a portion of one form of the improved fabric.

The rotary knitting machine which is disclosed 60 comprises a rotating needle cylinder in which the needles 2 are slidably mounted in the usual manner. In this machine the needles are moved up and down in a knitting wave to form stitches at two stitching points 65 by cams 4 and 6 respectively so that the successive courses formed by a thread or threads fed to the needles at one stitching point are separated by intermediate courses formed by a thread or threads fed to the needles at the 70 other stitching point.

The usual latch ring 8 is located above the needle cylinder and the usual sinker dial 10 in which sinkers 12 are slidably mounted to 75 cooperate with the needles. Below the sinker dial and also revolving with the needle cylinder is a jack dial 14 in slots in which jacks 16 are slidably mounted to engage pressers 18 and thereby deflect the hook ends of the needles inwardly, the jacks being moved at 80 the proper times by cam arms 20 and 22 (four of each being illustrated) engaging with suitably located butts formed on the jacks in different vertical positions. This mechanism is of the general type disclosed 85 in my applications Serial Nos. 209,383 and 341,374, filed July 29, 1927 and February 20, 1929, respectively.

At one stitching point, which will be hereafter referred to as the primary stitching point, three fingers 24, 26 and 28 feed yarns *a*, *b*, and *c*, respectively, to the needles as shown in Fig. 2, the yarns being preferably under decreasing tensions in the order *a*, *b* and *c*. While yarns *b* and *c* are fed to the outside of the circle of needles so as to be always engaged thereby, the yarn *a* is fed to a point inside the normal circle so that unless needles are deflected inwardly adjacent 95 yarns finger 24 they will fail to engage yarn 100

- a* which consequently floats. It is the function of cam arm 22 to press the needles inwardly at this point when they are to engage the yarn *a*. The cam 20 serves to deflect the needles rearwardly during the yarn drawing movement at the primary stitching point to reverse the yarns then in the hook thereof. These cams are operated by the usual pattern control mechanism.
- 10 In the modification of Figs. 1 and 2, a single finger 30 feeds a yarn *d* to the needles through a throat 32 in the latch ring at the secondary stitching point. As illustrated in Fig. 5, this finger is arranged to be removed when desired from operative position, for example, when knitting the heel and toe of hosiery, cams 6 being simultaneously rendered inactive so as to prevent the formation of a stitching wave at the secondary stitching point. When this occurs, the knitting proceeds with the yarn or yarns fed at the primary stitching point only.
- 15

While in the modification shown in Figs. 1 and 2 only a single finger is shown at the secondary stitching point, the construction of Fig. 9 shows an arrangement of fingers and cam arms at the secondary stitching point similar to that at the primary stitching point. That is, three fingers 34, 36 and 38 feeding yarns *e*, *f* and *g*, respectively, are provided, the needles being deflected inwardly to engage yarn *e* by one of the group of cam arms 42 and to reverse plate the yarns by one of the group of cam arms 40. The tensions of the yarns decrease in the order *e*, *f*, *g*. All of the fingers are arranged to be independently removed or simultaneously removed in the same manner and under the same conditions as arm 30.

20 Although preferred mechanisms are disclosed it will be clear hereafter that the improved process may be carried out to form the new fabrics by the use of other mechanisms: the type of mechanism disclosed in the Schubert application referred to above, for example, may be used in connection with two stitching points to carry out the process.

25 The various features of the process and new fabric will be clear by first considering the mechanism of Fig. 9 and the diagram of Fig. 8. In the diagram the possible constitution of the primary courses formed by yarns *a*, *b* and *c* are shown together with the constitution of the intermediate secondary courses formed by yarns *e*, *f* and *g*, it being understood that a wale of the fabric consists of loops alternately in the primary and secondary courses.

30 The terms "primary" and "secondary" courses used herein are not intended to imply that one is subsidiary to the other; this terminology being merely used to avoid confusion.

35 If, using all three yarns *a*, *b* and *c*, the needles are deflected inwardly by cam 22

so as to engage yarn *a*, and cam 20 is retracted from the jacks, loops of the type illustrated at portion *m* of the course are produced in which all three yarns are knitted in the order *a*, *b*, *c*, yarn *a* appearing on the face.

40 By maintaining cam 22 in the same position and by deflecting the needles inwardly by cam 20, the three yarns are reversed in the loops in the order *c*, *b*, *a*, as illustrated in portion *n* of the course.

45 If both cams are retracted from the jacks, yarn *a* floats and the others are knit into the loops in the order *b*, *c*, as shown in portion *o* of the course.

50 If cam 22 remains retracted but the needles are deflected inwardly by cam 20, loop *a* still floats but yarns *b* and *c* are knitted into the loops in the reverse order *c*, *b*, as in portion *p*.

55 Using the mechanism of the Schubert application, similar portions may be produced, the order in the triple reverse portion, however, being *c*, *a*, *b*.

60 By similar manipulations of cams 40 and 42 using the three yarns *e*, *f* and *g*, similar portions *q*, *r*, *s*, *t* may be produced in the secondary course as indicated in Fig. 8.

65 The enormous variety of designs producible will be obvious, inasmuch as the various portions of similar loops in the primary and secondary courses may be bounded by different wales as diagrammatically illustrated in Fig. 8 in which, for example, wales may consist of loops of a portion *q* of the secondary course lined up with loops of portions *n*, *o* and *p* of the primary course. In this manner most elaborate designs may be produced by pattern mechanisms operating the cams.

70 Clearly the six yarns need not be of different shades or colors nor need all of the yarns be used. When six yarns are used very intricate designs may be produced while nevertheless no loop contains more than three yarns, whereby the needless can properly handle the yarns and a fabric of light weight may be produced without using very light yarns.

75 Although three yarns are used in both the primary and secondary courses, and give a very large number of variations of design, more yarns may obviously be used; for example, two yarns instead of one, *a*, may be used, alternately floated to thereby produce additional effects. Yarn changes in either of the courses may serve to further increase the variations.

80 While two stitching points are shown forming primary and secondary courses in which a single secondary course is interposed between successive primary courses and vice versa, three or more stitching points may be used so that the loops of a wale are, in order, parts of three differently constituted courses.

The most elaborate form of fabric having a maximum number of variations has been described. There will now be considered several simpler but characteristic specific types of the fabric.

5 First, let it be assumed that either all three or any two of the yarns *a*, *b* and *c* are used while only one yarn *d* is used either guided by one finger of the mechanism of Fig. 9 or guided by the single finger of the simpler mechanism of Fig. 2, which latter is particularly designed for this type of fabric. Designs will then be produced by the manipulation of the yarns *a*, *b* and *c* by plating, reverse plating or floating in various combinations while the yarn *d* will form continuous successive courses of solid color as illustrated in Fig. 3, giving an appearance such as illustrated in Fig. 6 of a background containing designs viewed through the bars of a grating of the color of the yarn *d*. In Fig. 3 it will be noted that stitches of all four varieties *m*, *n*, *o* and *p* occur in the primary courses. In the fabric of Fig. 6 only two of the yarns are used in the primary courses.

Similar effects with elongated multi-colored bars are readily obtainable if more yarns than one are used in the secondary courses.

30 Another specific effect is easily obtained in simulation of the well known "wrap" effects. If a single yarn *d* is used in the secondary course and the yarn *a* is plated only in isolated chosen loops, being, preferably, floated behind the other loops, an effect similar to that shown in Fig. 7 is obtained, the yarn *a*, which is shown as solid black in that figure, appearing at points in a manner resembling a wrap yarn. If the yarn *a* is floated between its isolated appearances on the face of the fabric, the long floats are preferably cut from the fabric. One of the other yarns may, of course, be brought to the surface to give the "wrap" effect, being hidden elsewhere by plating. Or long floats of yarn *a* can be avoided by generally hiding the yarn *a* in loops of the type *n*. Instead of one yarn only being used in the secondary courses, others may also be used in connection with the "wrap" effect.

In the fabric just discussed the "wrap" effect is produced by a yarn in one group of courses only. If yarns in both primary and secondary courses are used to form "wrap" effects by being brought to the surface in isolated loops, very intricate results may be obtained since effects are producible which appear to result from two crossed wrap yarns, such effects being generally unobtainable by actual wrapping because of interference of the two yarns. Of course, if three or more different sets of courses are used very elaborate "wrap" effects are producible.

65 Fig. 10 shows an example of the elaborate

effects producible by using six yarns even though all the possible arrangements are not used. In this figure the yarns and illustrative loops are designated in accordance with Fig. 8. It will be seen that yarns *a* and *e* are used to produce "wrap" effects by being brought to the surface of a few isolated loops. These yarns are handled differently. Yarn *e* is floated behind all the loops except the isolated ones in which it appears on the surface. Accordingly it is necessary to cut the long floats from the back of the fabric: that is, the yarn is cut away from behind the second course in Fig. 10 in which it does not appear at all. On the other hand, yarn *a* is knitted in both loops *m* and *n*, and floats behind loops *o* only. If the loops *o* are relatively few, the yarn *a* will extend continuously along the successive courses without the formation of long floats which must be cut out.

An illustration of how a "grating" effect is secured is given in the second course in Fig. 10 in all of the loops of which yarn *g* appears on the surface.

Besides the advantages of the production of elaborate designs in a simple manner and without necessitating the formation of unduly heavy fabrics, the use of a plurality of courses increases the speed of production since a single revolution of the needle cylinder forms two or more courses.

In the following claims where a definite number of series of courses or yarns, or the like, is referred to, it is not intended, unless specifically so stated, to exclude other series of courses or yarns not referred to; for example, where it is stated that a loop includes two yarns, it is not intended to exclude the presence of a third yarn in the loop designated.

What I claim and desire to protect by Letters Patent is:

1. A knitted fabric including at least two series of courses with courses of one series between successive courses of the other series, the two series being formed by separate yarns, the courses of one series having one portion in which two yarns are knit into loops with one of the yarns overlying the other of the yarns, and another portion in which the two yarns are knit into loops with the second yarn overlying the first yarn.

2. A knitted fabric including at least two series of courses with courses of one series between successive courses of the other series, the two series being formed by separate yarns, the courses of one series having one portion in which two yarns are knit into loops with one of the yarns overlying the other of the yarns, and another portion in which only the first of the said yarns is knit into loops.

3. A knitted fabric including at least two series of courses with courses of one series between successive courses of the other series,

- the two series being formed by separate yarns, the courses of one series having one portion in which two yarns are knit into loops with one of the yarns overlying the other of the 10 yarns, another portion in which the two yarns are knit into loops with the second yarn overlying the first yarn, and still another portion in which only one of the said yarns is knit into loops.
- 10 4. A knitted fabric including at least two series of courses with courses of one series between successive courses of the other series, the two series being formed by separate yarns, the courses of one series having one portion in which three yarns are arranged in one predetermined manner with one of the 15 yarns appearing on the surface, and another portion in which another yarn appears on the surface.
- 20 5. A knitted fabric including at least two series of courses with courses of one series between successive courses of the other series, the two series being formed by separate yarns, the courses of one series having one portion in which three yarns are arranged in one predetermined manner with one of the 25 yarns appearing on the surface, and another portion in which the other two yarns are knitted into loops in plated relationship.
- 30 6. A knitted fabric including at least two series of courses with courses of one series between successive courses of the other series, the two series being formed by separate yarns, the courses of one series having one portion in which three yarns are arranged in one predetermined manner with one of the 35 yarns appearing on the surface, another portion in which the other two yarns are knitted into loops in plated relationship, and still another portion in which the last mentioned 40 two yarns are knitted into loops in a reverse plated relationship.
7. The process of knitting a fabric which includes manipulating needles and cooperating members at, at least, two spaced points to form loops in yarns fed to the needles adjacent said points, and manipulating the 45 yarns at one of the points to selectively produce normal or reverse plating of a plurality of yarns at that point.
8. The process of knitting a fabric which includes manipulating needles and cooperating members at, at least, two spaced points to form loops in yarns fed to the needles adjacent said points, and manipulating the 50 yarns at one of the points to selectively produce loops containing a plurality of the yarns in normal or reverse plated relationship, or to cause at least one of the yarns to float.
- 60 60. In testimony of which invention, I have hereunto set my hand, at Philadelphia, Pennsylvania, on this 28th day of October, 1929.
- WILBUR L. HOUSEMAN.
